(57) **CLAIM**

The ornamental design for a skateboard, as shown and described.

DESCRIPTION

FIG. 1 is a perspective view of a skateboard showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear side perspective view thereof;

FIG. 9 is an enlarged view of a skateboard taken from the circle part in FIG. 1; and,

FIG. 10 is an enlarged view of a skateboard taken from the circle part in FIG. 8.

Any shading and cross-hatching are not features of the design but are utilized to illustrate the surface contours of the skateboard design in the drawings.

The broken lines in the drawings depict portions of the skateboard that form no part of the claimed design.
